Assistant Examiner — Michelle Marquart Christeon

(74) **Attorney, Agent, or Firm** — Hamilton, Brook, Smith & Reynolds, P.C.

(57) **CLAIM**

The ornamental design for a cannula securing device, as shown and described.

DESCRIPTION

FIG. 1 is a front upper perspective view of the cannula securing device.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines show portions of the cannula securing device that form no part of the claimed design.

1 Claim, 7 Drawing Sheets
